UNITED STATES PATENT OFFICE.

WILLIAM WALKER, OF SUMMIT, NEW JERSEY.

DESIGN FOR A COAT, HAT, AND UMBRELLA HOOK.

SPECIFICATION forming part of Design No. 27,963, dated December 7, 1897.

Application filed October 27, 1897. Serial No. 656,591. Term of patent 7 years.

To all whom it may concern:

Be it known that I, WILLIAM WALKER, a citizen of the United States, residing at Summit, Union county, New Jersey, have invented 5 a new and original Design for a Combined Coat, Hat, and Umbrella Hook, of which the following is a full, clear, and exact description.

My invention relates to a new and original 10 design for a combined hat, garment, and umbrella hook.

Referring to the accompanying drawing, the figure thereon illustrates a perspective 15 view of a combined hat, garment, and umbrella hook embodying my new and original design.

The leading features of my design comprise the general outlines and configuration hereinafter fully set forth, in which A is a sub- 20 stantially flat central body portion. B is a

beak projecting downwardly from said body portion, which beak terminates in a forwardly and upwardly curved end. C C are wings downwardly directed from said body portion, said wings being curved rearwardly at points 25 intermediate in their length and terminating in rounded ends. D D are horns projecting upwardly from said body portion and curved outwardly and then upwardly and terminating in rounded ends. Said horns D D diverge, 30 as shown.

What I claim is—

The design for a combined hat, garment and umbrella hook, substantially as herein shown and described.

WILLIAM WALKER.
